CLAIM

The ornamental design for a connector assembly for a tool grip, as shown and described.

DESCRIPTION

FIG. 1 is perspective view of the connector assembly for a tool grip, in a first position in relation to a tool in stippled lines;

FIG. 2 is an enlarged view of the connector assembly for a tool grip, in the first position;

FIG. 3 is perspective view of the connector assembly for a tool grip, in a second position in relation to a tool in stippled lines;

FIG. 4 is an enlarged view of the connector assembly for a tool grip, in the second position;

FIG. 5 is a front of the connector assembly for a tool grip;

FIG. 6 is a first side view thereof top of the connector assembly for a tool grip;

FIG. 7 is a top view thereof side of the connector assembly for a tool grip;

FIG. 8 is a second side of the connector assembly for a tool grip; and,

FIG. 9 is a bottom of the connector assembly for a tool grip. The broken lines shown in FIG. 1-9 illustrate portions that form no part of the claimed design.

1 Claim, 6 Drawing Sheets
